UNITED STATES PATENT OFFICE

CHARLES H. SEMPLE, OF TRENTON, NEW JERSEY.

DESIGN FOR A RESILIENT TIRE.

43,439.

Specification for Design.

Patented Jan. 7, 1913.

Application filed July 16, 1912. Serial No. 709,827. Term of patent 14 years.

To all whom it may concern:

Be it known that I, CHARLES H. SEMPLE, a citizen of the United States, residing at Trenton, in the county of Mercer and State of New Jersey, have invented a new, original, and ornamental Design for Resilient Tires, of which the following is a specification, reference being had to the accompanying drawings, forming part thereof, in which—

Figure 1 is a plan of a portion of a resilient tire suitable for use on an automobile, showing my new design; and Fig. 2 is a side elevation of the same.

Referring to the drawing, the longitudinally and transversely curved tread surface of the tire 1 is provided with a centrally disposed group of parallel circumferential ribs 2, separated from each other by intervening parallel grooves 3. Forming substantially the lateral limits of the tire tread proper are circumferential bounding ribs 4, ar-

ranged one on each side of the group of ribs 2 and parallel therewith and spaced away from the central group of ribs by grooves 5. Bounding ribs (4) are continuous around the circumference of the tire, while ribs (2) are interrupted by a series of grooves 6 extending obliquely thereacross, alternate grooves being parallel to each other, and the ends of adjacent grooves being nearly contiguous, to simulate a continuous zig-zag or angling groove extending entirely around the tire circumference. The depth of these oblique grooves is substantially the same as that of the circumferential grooves (3).

I claim:

The ornamental design for a resilient tire as shown and described.

CHARLES H. SEMPLE.
